CATHERINE E. WHITE

Ladies' Hood.

No. 6,209.

Patented Oct. 15, 1872.

UNITED STATES PATENT OFFICE.

CATHERINE E. WHITE, OF BALTIMORE, MARYLAND.

DESIGN FOR A LADY'S HOOD.

Specification forming part of Design No. 6,209, dated October 15, 1872.

To all whom it may concern:

Be it known that I, CATHERINE E. WHITE, of Baltimore, Maryland, have invented a Design for Ladies' and Children's Hood with Cape, of which the following is a specification:

The nature of my design for a hood with cape is fully represented in the accompanying drawing.

I am aware that hoods with capes cut in one piece have been made and are now in the market, and do not claim that as my invention.

The distinctive character of my design con-

sists in the peculiar cut to make it fit under the chin, and the peculiar manner of ornamentation by means of the elastic cord at the top, the binding, and the parallel trimming, all of which is shown in the drawing.

I therefore claim—

A design for a hood, with cape cut and ornamented, substantially as shown.

MRS. CATHERINE E. WHITE.
